CLAIM

The ornamental design for a tire, as shown and described.

DESCRIPTION

FIG. 1 is a perspective view of a tire embodying my new design, it being understood that the pattern is repeated throughout the circumference of the tire, the opposite side being substantially the same as that shown; FIG. 2 is a front elevational view thereof; FIG. 3 is a side elevational view thereof; FIG. 4 is an enlarged fragmentary cross-sectional perspective view of a segment of the tread thereof; FIG. 5 is an enlarged fragmentary cross-sectional perspective view of the groove area of the tread segment shown in FIG. 4 bounded by the ellipse designated as FIG. 5 therein; and, FIG. 6 is a greatly enlarged fragmentary cross-sectional view through the sipe in the groove taken along line 6—6 in FIG. 5.

FIG. 1

FIG. 2

FIG. 3

FIG. 4

FIG. 5

FIG. 6
